UNITED STATES PATENT OFFICE.

CLARENCE D. MILLER, OF PHILADELPHIA, PENNSYLVANIA, ASSIGNOR TO MESCO MOTOR COMPANY, OF PHILADELPHIA, PENNSYLVANIA, A CORPORATION OF DELAWARE.

INTERNAL-COMBUSTION ENGINE.

1,185,339.

Specification of Letters Patent.

Patented May 30, 1916.

Application filed January 2, 1915. Serial No. 57.

To all whom it may concern:

Be it known that I, CLARENCE D. MILLER, a citizen of the United States, residing at the city of Philadelphia, in the county of Philadelphia and State of Pennsylvania, have invented certain new and useful Improvements in Internal-Combustion Engines, of which the following is a specification.

My invention relates to that class of internal combustion engines known as a rotary valve type, in which puppet valves are not used as I use a circular sleeve or ring in place thereof with an opening or port, the sleeve usually being slit or cut and when cut it is usually at or near the said opening or port. This form of motor and valve is more simple in construction, cheaper to manufacture, and has less parts than other types of motors which use the puppet or sleeve valves.

The principal objects of the present invention are to improve internal combustion engines, more particularly in respect to the valves and their accessories; to reduce the number and simplify the construction of the valve parts and so to provide a comparatively inexpensive internal combustion engine; to provide for holding comparatively high compression and thus effecting economy in operation; to so construct and combine the parts that they will be quiet in operation, will not be interfered with by deposition of carbon and will require comparatively few repairs which, as well as adjustments, can be readily made; and to avoid the use of parts which are expensive to make and require re-grinding at intervals to maintain them in proper condition.

One object of my invention includes an internal combustion engine having a sleeve or ring or sleeves or rings mounted upon a hollow stud or shaft with a collar either integral with said stud or shaft, or bolted or screwed to said stud or shaft. In referring to the ring or sleeve I do not confine myself to one such ring or sleeve, but it may be several such rings or sleeves in each and every case.

Another object of my invention is to have a sleeve or ring with an opening or port, mounted upon a stud or shaft, said stud or shaft being hollow, with an opening or port, to allow an incoming charge of gas or vapor to enter to produce the necessary explosion,

with means for permitting the gas or vapor after it has been exploded to be expelled or passed out through the opening or port.

Another object of my invention covers the use of a ring or sleeve, being split as described, and in which the natural expansion and contraction of the metal has the effect of opening or closing the valve to produce and retain the described and requisite compression necessary in an internal combustion engine.

Another object of my invention is to have the sleeve or ring so mounted on the stud or shaft that when the gas or vapor is admitted through the opening or port, the sleeve or ring will partially rotate or revolve with the stud or shaft in such a manner, that when the charge of gas or vapor is admitted, the sleeve will rotate or partially revolve properly and thus allow the expulsion of the exhaust gas or vapor after explosion.

Another object of my invention is to have the sleeve or ring on the stud or shaft mounted in such a manner that the opening or port registers so that the two ports, namely the sleeve port opening and the port opening in the stud work in unison with the opening or port in said stud or shaft.

Another object of my invention is to have the stud or shaft with the opening or port have a collar bearing upon a thrust bearing over or under said collar, so that the partial rotary motion may be accomplished without undue strain or wear on any of the parts.

Another object of my invention is to have the stud or shaft with the opening or port having a collar, and having means whereby a gear or gears may be attached to or fastened on the said stud or shaft, which gear or gears are in turn connected with a shaft running at or about right angle thereto, the said latter shaft having gears which mesh with those on the stud or shaft for the purpose of proper timing of the revolutions and explosions of the motor.

Another object of my invention is to have the sleeve or ring with the opening or port, the stud or shaft, the collar, and the gear or gears in such position that a cap or housing may be placed over the gears without disturbing, changing, or interfering with the alinement or proper working of the parts of the internal combustion engine, thereby

producing a new, useful, and cheap method of manufacturing an engine of the type described, that is accessible in all its working parts merely by removing a cap or housing, 5 either when the engine is in operation or not running.

My invention also covers the construction of an internal combustion engine as above described, but is not limited to the use of 10 one sleeve or ring, but to any number that may be desired to accomplish the same or equivalent purpose.

My invention also includes various improvements in the construction of internal 15 combustion engines and in the parts hereafter described and specifically combined as referred to, and I do not limit myself in either my specifications or claims to the particular forms of the parts described and 20 illustrated, but other forms producing the same or equivalent results are covered by my invention.

My invention relates to either air or water 25 cooled internal combustion engines, but a thermo-siphon or water cooled engine is shown in my drawings, but I do not limit myself to that construction.

The invention will be claimed at the end 30 hereof but will be first described in connection with the embodiment of it chosen for illustration in the accompanying drawings forming part hereof, and in which—

Figure 1, is a side view partly in section 35 of an internal combustion engine embodying features of the invention. Fig. 2, is a sectional view drawn to an enlarged scale and illustrating features of the invention. Fig. 3, is a perspective view of one of the parts detached, and Fig. 4, is a transverse sectional view of Fig. 2.

In the drawings 1, is a valve casing provided with a cylindrical opening that extends clear through it and constitutes a valve seat and with an intake port 2, and 45 an exhaust port 3. The valve seat is provided at the end thereof where it communicates with the cylinder 4, and a contracted shoulder 5. At the top of the valve seat there is an enlarged shoulder 6.

50 7, is a stud provided with a collar 8, and with a hollow valve body 9, having a port 10, formed through the wall thereof. The elements 7, 8, and 9, may be made integral or they may be suitably connected together 55 so as to constitute in effect one piece. The rim of the valve 9, near one end has a bearing in the portion 11, of the valve seat beyond the shoulder 5, and the collar 8, has a bearing in the valve seat inside of the 60 shoulder 6.

65 12, is a bearing ring through which the stud 7, passes and which is seated upon the shoulder 6, and which is provided with an extension that is seated on the collar 8.

13, is a locking ring that encircles a boss

on the bearing ring and has screw and thread engagement with the valve seat and serves to hold the bearing ring.

14, is a sleeve split as at 15, and provided with a port 16, aligned with the port 10. This split sleeve 14, is arranged between the valve 9, and the wall of the valve seat and extends from the shoulder 5, to the inner face of the collar 8. This split sleeve is contracted when it is put in place and hence it 75 tends by its resiliency or springiness to expand and hug the inner face of the valve seat. A pin 17, is shown as an example of a means for keeping the ports 10 and 16, opposite each other. On the stud 7, there 80 is a worm gear 18. The drive shaft 19, is provided with a number of worms 20, one for the worm wheel of each valve, and the valve bodies 9, of the different cylinders 4, are so set with regard to their ports 10, and 85 the inlets and exhausts that the operation of the various pistons and cylinders are properly timed. The shaft 19, is shown as driven from the crank shaft 22, by means of a shaft 23, and gearing 24.

90 25, is an oil feeder. The valve casing is provided with walls 26, which together with the removable cover 27, constitute an oil receptacle in which the valves and their accessories are arranged. When the cover 95 27, is removed, access may be readily had to the valves and their parts.

26 The split sleeve 14, is contracted when it is arranged in the valve casing and it tends to open so that it hugs the curved wall of 100 the valve chamber in which it is arranged. The valve chamber is subject to expansion and contraction under the heat to which it is exposed but the split sleeve by expanding and contracting compensates for this while 105 at the same time properly holding the compression in the cylinder so that the valves can be easily rotated and do not tend to stick or jam. The compression in the cylinder is not only held by the sleeve but also by the 110 collar 8, in coöperation with the bearing ring 12.

115 It will be obvious to those skilled in the art to which the invention relates that modifications may be made in details of construction and arrangement without departing from the spirit of the invention, hence the latter is not limited as to those matters or in any way further than the prior state of the art and the appended claims may require.

120 What I claim is:

1. In an internal combustion engine the combination of a valve casing having a cylindrical seat extending through it and provided at its inner end with a shouldered contraction and near its outer end with a shouldered enlargement, and said casing also having ports communicating with said seat between said shoulders, a valve member ex- 125 130

tending through said seat and comprising a rotary hollow valve body opening through the inner end of the seat and provided with a radial port and an enlarged collar, a locking bearing ring abutting on the collar and arranged in the enlargement, and a split expansion sleeve between the valve body and seat and collar and shouldered contraction and provided with a port alined with the 10 valve body port.

2. In an internal combustion engine a valve casing having a cylindrical seat, a rotary valve in said seat, a collar on the valve, a bearing ring for the collar, and a split 15 sleeve encircling the valve, substantially as described.

3. In an internal combustion engine the combination with the piston chamber, of a valve chamber, a ported valve sleeve within 20 the valve chamber, a member comprising a stud, collar and ported valve-body, the latter within the sleeve and attached thereto, and gearing through which the stud is rotated and properly timed.

25 4. In an internal combustion engine, the combination with the piston chamber, of a valve chamber, a ported valve sleeve within the valve chamber, a member comprising a stud, collar and ported valve-body, the latter 30 within the sleeve and attached thereto, gearing to rotate the stud, and a cap or housing for the gearing.

5. An internal combustion engine consisting of a crank shaft, connecting rods, pistons and piston rings, water jackets, hollow 35 stud, surrounded by a hollow sleeve, with a port or ports, and surrounded by a sleeve with a port or ports, and with a thrust collar, thrust bearing, driving gears and pinions, and means for holding same in position.

6. In an internal combustion engine, the combination with the piston chamber, of a valve chamber of relatively small diameter communicating therewith, a rotatable ported valve body within and spaced from the inner 45 wall of the valve chamber and adapted to sustain the pressure of exploding and compressed gases, and a ported split valve sleeve encircling the valve body and occupying the space between it and the inner wall of the valve 50 chamber and attached to the valve body so as to rotate therewith.

7. In an internal combustion engine, the combination with the piston chamber, of a valve chamber communicating therewith, a 55 rotatable ported valve body within the valve chamber and seated against a constricted portion of the valve chamber and adapted to sustain the pressure of exploding and compressed gases, and a ported split valve sleeve 60 surrounding and connected to the valve body and occupying the space within the enlarged portion of the valve chamber outside the valve body.

8. In an internal combustion chamber, the 65 combination with the piston chamber, of a valve chamber communicating therewith, a stud having a collar and a ported valve body portion within the valve chamber, and a ported split valve sleeve encircling and attached to the valve body and bearing at its, upper end against the collar and at its lower end against a contracted part of the valve chamber.

In testimony whereof I have hereunto 75 signed my name.

CLARENCE D. MILLER.
